United States Patent Office

Des. 222,026
Patented Sept. 28, 1971

222,026

PAINT APPLICATOR

Elias J. Johnson, 503 Stevens St.,
Green Bay, Wis. 54303

Filed June 22, 1970, Ser. No. 23,586

Term of patent 14 years

Int. Cl. D4—04

U.S. Cl. D4—38

FIG. 1 is a view in perspective of a paint applicator embodying my new design.

FIG. 2 is a plan view thereof.

FIG. 3 is a side view in elevation.

FIG. 4 is a similar view facing one apex of the triangular base thereof.

FIG. 5 is an inverted plan view thereof.

I claim:

The ornamental design for a paint applicator, as shown.
